UNITED STATES PATENT OFFICE.

MARIUS R. DAHLGREN, OF OAKLAND, CALIFORNIA, ASSIGNOR OF ONE-
THIRD TO JOHN YULE, OF SAME PLACE.

RAILROAD-SWITCH.

SPECIFICATION forming part of Letters Patent No. 251,417, dated December 27, 1881.

Application filed May 11, 1881. (No model.)

To all whom it may concern:

Be it known that I, MARIUS R. DAHLGREN, of Oakland, county of Alameda, and State of California, have invented an Improved Railroad-Switch; and I do hereby declare the following to be a full, clear, and exact description thereof.

My invention relates to certain improvements in railroad-switches; and it consists in a novel combination of apparatus which is connected with the switch-rail to be moved, and has extensions in each direction with crank arms or disks. These arms are so placed that devices carried upon the locomotive may be thrown out, so as to strike either one or the other, and thus throw the switch-rail in either direction desired, and when approaching the switch from either direction or upon either branch, as will be more fully explained by reference to the accompanying drawings.

Figure 1 is a general view, showing the relative arrangement of parts upon the track and upon the train. Fig. 2 is an enlarged view of the device for throwing the switch-rail. Fig. 25 3 is a vertical section of the crank-wheel or disk. Fig. 4 is a view of the rope-pulley and the method for connecting the rope therewith. Figs. 5, 6, and 7 are views of the operating-levers and their construction.

30 A A and B B are two lines of track, and C C are the throw or switch rails, by which either of these lines may be connected with the main line of which the switch-rails form a part. The moving ends of the rails C are united by a rigid bar, D, which has chairs formed at each end to receive and hold the bottom flanges of the rails, as shown. The remaining part of the rails are united by tie-rods in the usual manner. The free end of the rails and their uniting-bar are moved from side to side to connect with one or the other of the rails A B by a system of levers, which are constructed as follows:

45 E F are two links, which are hinged or joined together in the center to form a knee-lever. The outer end of the link E is pivoted to the bar D near the rail upon that side, while the inner end of the link F is pivoted to a fixed standard, G, at a central point between the two rails. Two similar links, H and I, are hinged

together and occupy a similar position upon the other side of the standard G, being also united to it and the bar D by their outer and inner ends in a similar manner, as described, for the links E F, so that the four links extend across beneath the bar D, the two inner ones being hinged together and to the standard G at the center, and the two outer ones being hinged or jointed to their outer ends and to points near the ends of the bar D. These links are longer than the distance between the points where their outer ends are connected with the bar D, so that when one pair, E F, are in a straight line the pair H I will be bent to form a knuckle-joint, and when this pair are straight 55 the pair E F will form a knuckle-joint, as shown in Fig. 5. By this construction it will be seen that when one pair of links are bent and the other straightened the bar D and the rails will be forced to the side of the straight 60 links, the bending of the joint between the others allowing the rail to approach upon that side, while a reversal of movement will throw the rails to the opposite side. It will also be seen that the pair of links which are in a straight 65 line serve as a lock or brace to prevent the rails from being moved from their position. In order to operate these links I employ a double-ended lever, J, which is pivoted at K, while the ends are connected with the joints between 70 E F and H I by links L, so that when the lever is turned to one side or the other one pair of links, E F or H I, will be straightened and the other pair drawn into an angle simultaneously.

In some cases it may be found desirable to 75 employ a chain-connection between the lever J and the links E F H I, when a second cross-lever, M, will be fixed opposite the lever J, and the ends of the chains are also secured to this lever, so that the chains are kept strained between the two levers J M, and the levers work 80 together.

At the end of the lever J, opposite the fulcrum K, are eyes N, to which chains, ropes, or other strong flexible connections O are secured. 95 These lead outside the rails and over pulleys P, passing thence parallel with the track to points sufficiently distant from the switch-rail in each direction, where they are secured to pulleys Q. These pulleys are mounted on spindles which 100

pass up through disks R, forming the tops of the pulley-cases, and these disks have stout cranks S, projecting up from one side, as shown, so that when struck by an arm which may be thrown out from the side of the locomotive the disk and pulley will be rotated, the ropes or chains moved, and the levers actuated so as to throw the rails to one side or the other. This mechanism is all placed beneath the surface, except the operating-cranks, and is suitably incased and protected.

The cranks S are moved by arms T, which are hinged to a frame-work, U, or to some portion of the locomotive, so that either one may be thrown out at will. In the present case I have shown the knee-levers V united to form a knuckle-joint at W. The inner ends of the inner levers are pivoted to the frame and the ends of the outer levers to the arms T.

Each pair of levers has a spring, X, connected with the joint W, so that it will draw upon the joint and bring the levers to an angle, thus drawing the arms T closely in to the sides of the frame.

Cords or chains Y lead from the joints to some point within easy reach of the engineer, so that he can, by pulling upon either of them, draw the joint back until the levers V on either side are in a straight line. This throws the arm T out upon one side so far that it will strike the crank-arm S upon that side, and through the pulley, rope, and levers throw the switch upon the side desired. When the levers V are in a straight line they also act as a brace to resist and hold the arm T in place and

prevent its being forced back by the blow upon the crank S when passing.

By means of this apparatus I am enabled to control the switch-rail and alter its position from the approaching train at will. ⁴⁰

Having thus described my invention, what I claim as new, and desire to secure by Letters Patent, is—

1. The levers E F and H I, connected with a stationary center and with the switch-rails 45 upon each side, so that by straightening one pair of levers and bringing the other to an angle the switch-rails may be moved from side to side, in combination with the lever J and connecting links or chains L, substantially as 50 herein described.

2. The knee-levers E F and H I, connected with the switch-rails, as shown, in combination with the lever J and links or chains L, the flexible connections O, and the pulleys Q, and 55 crank arms or disks R S, substantially as and for the purpose described.

3. The knee-levers E F H I, connected with the switch-rails, the lever J, flexible connections O, and cranks S, in combination with 60 the hinged arms T, knee-levers V, chains or ropes Y, and springs X, substantially as and for the purpose herein described.

In witness whereof I have hereunto set my hand.

MARIUS R. DAHLGREN.
